UNITED STATES PATENT OFFICE.

GEORGE D. CLAPP, OF BOSTON, MASSACHUSETTS.

DESIGN FOR A WELT-STRIP.

SPECIFICATION forming part of Design No. 33,014, dated July 24, 1900.

Application filed May 21, 1900. Serial No. 17,491. Term of patent 14 years.

To all whom it may concern:

Be it known that I, GEORGE D. CLAPP, a citizen of the United States, residing in Boston, county of Suffolk, and State of Massachusetts, have invented and produced a new and original Design for a Welt-Strip, of which the following is a specification, reference being made to the accompanying drawings, forming a part thereof.

Figure 1 is a plan view of my welt-strip, and Fig. 2 is an edge view of the same.

The leading or material feature of my design for a welt-strip consists in a continuous U-shaped strip of material of the same width

and thickness throughout, comprising parallel portions *a a*, a semicircular portion *b*, and rounded portions *c c*.

I claim—

The design for a welt-strip, as herein shown and described.

In testimony whereof I have signed my name to this specification in the presence of two subscribing witnesses.

GEORGE D. CLAPP.
